SLEEPING BAG

George E. Rycroft, Waban, Mass.

Application March 8, 1932, Serial No. 597,505

1 Claim. (Cl. 5—343)

This invention relates to sleeping bags and it aims to devise an article of this character which can be manufactured economically and sold at a cost substantially lower than that of the better 5 grades of sleeping bags now obtainable, while still being light in weight and suitable for use in cold weather and in severe climates.

The nature of the invention will be readily understood from the following description when 10 read in connection with the accompanying drawings, and the novel features will be particularly pointed out in the appended claim.

In the drawings,

Figure 1 is a plan view of a sleeping bag constructed in accordance with this invention;

Fig. 2 is a side elevation of the bag shown in Fig. 1;

Fig. 3 is a perspective view of the upper part of the bag showing it partly closed and a hood 20 turned somewhat toward the left;

Fig. 4 is a detailed sectional view approximately on the line 4—4, Fig. 1;

Fig. 5 is a rear view of the hood;

Fig. 6 is a front view of a detachable hood;

Fig. 7 is a perspective view of the entire bag 25 rolled up and secured in a compact form; and

Fig. 8 is a sectional view on a large scale of a portion of the envelope and lining therefor shown in Fig. 4.

Referring more particularly to Figs. 1 and 2, the bag there shown consists of upper and lower sections 2 and 3, respectively. These sections are made substantially alike except that the upper section 2 has a cut-out or notch 4 to accommodate the neck of the wearer, whereas the corresponding edge of the bottom section 3 usually is made straight. The sections are secured together at their lower ends and along their sides by lines of stitching 5. However, the 30 stitching terminates at an intermediate point on each edge of the bag, and the top of the bag and the sides down the lines of stitching are provided with slide operated fasteners such as those known commercially as hookless fasteners, talon 35 fasteners, and zippers. Each of these fastening devices includes two rows of interlocking elements 6 and a cam slide 7 for moving said elements into and out of the interlocking engagement with each other. Customarily each row of 40 elements 6 is secured to a tape-like strip 8 which is stitched to the margin of one of the sections in a manner well understood by those familiar with fastening devices of this character. Such an arrangement permits the wearer to open the 45 entire upper portion of the bag for a considerable

distance, as shown, for example, in Fig. 1, to facilitate getting into and out of the bag, or turning it inside out for airing.

An important feature of this invention resides in the structure of the sections 2 and 3. Referring more particularly to Figs. 4 and 8 it will be seen that each section is of a ply formation. Each includes an outer sheet 10 of waterproof material, an inner lining 12 of some relatively thick flexible heat insulating fabric or equivalent material, and an intermediate layer or ply 14 of sheet material having an open fibrous or fuzzy structure so that it will retain a fairly thick body of air. Preferably the outer sheet 10 consists of a rubberized 60 fabric combined with the intermediate sheet 14, 70 the latter consisting of a napped fabric such as cotton flannel, canton flannel, or the like. These two sheets are secured together by a waterproof adhesive, usually of a rubbery nature. Preferably, also, the rubberized waterproof sheet 10 carries 75 an outer coating of flock so that it resembles a suede leather. The inner lining 12 may consist of a heavy, warm fabric, such for example, as a blanket fabric. I prefer, however, to make this lining of a good grade of felt which has been 80 heavily calendered so that it is made relatively compact and is given a hard surface finish. It will be evident that a rubberized sheet has, of 85 and by itself, relatively little heat insulating value. In fact, it transmits heat fairly readily 90 and for this reason is regarded as a "cold" material. This object is avoided to a substantial degree by coating the outer surface of the fabric with short fiber, such as that known commercially as "frock", such a coating having the further 95 advantage of improving very greatly the surface appearance and feel of the goods. By making the lining 12 of felt or some other fabric which has considerable resistance to the passage there- 100 through of air and interposing an air retaining layer 14 of fabric between it and the outer sheet 10 which is substantially impervious to both air and water, an air space is provided between the outer sheet 10 and the lining 12 which forms an exceptionally good thermal insulator. A hard 105 calendered felt also is of advantage in decreasing the tendency of dirt and foreign materials to stick to it. At the same time it is warm and flexible.

As above stated, the top and bottom sections 110 are substantial duplicates, and they are secured together at their margins, the edges of each section being inturned as shown clearly in Fig. 4. Consequently, the finished bag includes an outer envelope which is waterproof and which almost

completely encloses the lining and inner layers. In order to hold the lining 12 and the outer waterproof sheet 10 in approximately a fixed relationship to each other, these sheets of each section 2 and 3 are stitched together, preferably on diagonal lines, as indicated at 15, Fig. 1.

A hood 16 made of the same material as that of which the bag is composed preferably is provided and it may either be secured permanently to the upper edge of the lower section 3, as shown in Figs. 1, 2, 3 and 5, or it may be provided with button holes 17, Fig. 6, so that it can be removably fastened to the upper edge of said section.

It is also desirable to fasten a strap 18 permanently to the bag as by stitching on lines indicated at 19, Fig. 3, where it can be conveniently wrapped around the bag when the latter has been rolled up, the strap being provided with a buckle 20 for fastening it to hold the bag in a compact form.

I have found that a sleeping bag can be made in the manner above described which will weigh between six and seven pounds and still will have ample warmth so that a person can sleep comfortably in it outdoors in relatively cold weather. Additional warmth can be provided by properly folding a blanket and inserting it into the bag, the wearer sleeping inside both the blanket and

the bag. Or, an inner bag may be made of heavy blanket material and used inside the bag. Such a bag can be manufactured at an expense substantially less than that of even the more reasonably priced bags at present on the market, and it satisfies the requirements for a considerable class of campers and outdoor enthusiasts, boy scouts, and others, who require a warm and serviceable bag but one of light weight.

While I have herein shown and described a preferred embodiment of my invention, it will be understood that the invention may be embodied in other forms without departing from the spirit or scope thereof.

Having thus described my invention, what I desire to claim as new is:

A sleeping bag comprising an outer envelope of waterproof rubberized sheet material externally coated with flock, an inner lining of relatively thick flexible heat insulating fabric, a layer of open fibrous air retaining sheet material between said envelope and said lining adapted to hold a body of air of considerable thickness constantly separating said lining and said envelope, and means for holding said envelope, lining and layer in approximately fixed relationship to each other.

GEORGE E. RYCROFT.
